GIOVANNI EMANUELE ELIA, OF PARIS, FRANCE, ASSIGNOR TO VICKERS LIMITED, OF WESTMINSTER, ENGLAND.

INERTIA DEVICE FOR CONTROLLING THE FIRING OF SUBMARINE MINES.

1,305,080.

Specification of Letters Patent. Patented May 27, 1919.

Application filed September 15, 1914. Serial No. 861,834.

To all whom it may concern:

Be it known that I, GIOVANNI EMANUELE ELIA, a subject of the King of Italy, and residing in Paris, France, Hotel de Crillon, Place de la Concorde, gentleman, have invented certain new and useful Improvements in and Relating to Inertia Devices for Controlling the Firing of Submarine Mines, of which the following is a complete specification.

10 This invention relates to an inertia device for controlling the firing of submarine mines, more particularly applicable to mines in which the firing is produced by the rotation of the mine in contact with a moving ship. The invention has particularly in view to permit of the operation of the firing mechanism without it being necessary to provide a stationary supporting point on 15 the hull of the ship.

20 In the accompanying drawing, an embodiment of the invention is shown by way of example.

Figure 1 is an assembly view of the firing mechanism;

25 Fig. 2 is a plan thereof.

The percussion pin *a* of the mine disposed opposite the detonator *b* of a usual type, is integral with the rod *c* formed with the shoulder *d* under which the spring *e* controlling the percussion pin is located. This rod or spindle is terminated at its lower end in known manner by a square head *f* held by the claws *g* pivoted on the axis *h* of the 30 ring *i* of the mooring cable.

35 The percussion pin comprises a head or piston *j* adapted to slide in a cylinder *k* the wall of which is formed with openings *m* of which there are a suitable number to permit of the passage of the inner claws *n* of the levers *o* pivoted at *p*. Each of these levers, suitably curved as shown in the drawing, is provided at its lower part with a roller *q*, preferably ball mounted, bearing 40 on an inner flange *r* of a flywheel *s* located within the mine, and provided with a hub *t* mounted on the cylinder *k* through the medium of a ball race.

45 The flange *r* is formed with the notches *u* the number of which corresponds to that of the rollers *q*, the dimensions of which are sufficient to permit any of the levers *o* to occupy the position shown in Fig. 1 in dotted lines.

50 In a flange of the hub *t* a notch is formed

engaged by the tip of a pivoted pawl *v*, the end of which is acted upon by a finger *x* provided with a spring *y*, and adapted to be maintained in the position illustrated in the drawing by a sal-ammoniac block *3*. 60

The detonator is disposed in the usual manner in proximity to the explosive charge provided in a cylinder *w* rendered integral in any suitable manner, with the body *z* of the mine which is preferably spherical. 65

The operation is as follows:

At rest the members occupy the position illustrated in the drawing, the stops *n* of the levers *o* (numbering four in the present case), retaining the head *j* of the percussion 70 pin, and as the rollers *q* of these levers bear on the circular shoulder *r* of the flywheel *s*, there cannot be a relative movement between the mine and its percussion pin. The members are moreover, maintained in this 75 position by the safety lock constituted by the pawl *v*.

When the mine is anchored, the sal-ammoniac block *3* melts so that the spring *y* pushes the finger *x* back and the pawl *v* 80 liberates the hub *t*. In this position, when the mine is struck by a moving ship, the body of the mine is in contact with the side of the ship and effects against the latter a continuous rotary movement owing to friction. The flywheel *s* which has a comparatively great mass and is supported in the interior of the mine solely by the ball race, does not participate in this rotary movement 85 so that it tends to produce a relative movement between the flywheel *s* and the body of the mine. A moment will therefore be reached where the rollers *q* which participate in the rotary movement of the mine, will be facing the notches or recesses 90 *u*. At this moment, the various arms of the levers being calculated exactly to this end, the buoyancy of the mine is sufficient to cause the oscillation of the levers *o* about their axes *p*. These levers then assume the 95 position shown in Fig. 1 in dotted lines and the projections *n* are released from the head *j* of the percussion pin. The mine rising, causes the spring *e* to tension until the claws *g* open and liberate the square end *f* of the 100 rod or spindle *c*. The percussion pin is then pushed back by its spring *e* so as to produce the firing of the mine.

Owing to this disposition, the firing of the mine may take place without it being 110

necessary to provide a lever or any other member bearing on the side of the ship during the rotation of the mine. The whole of the mine and its members is thus rendered more homogeneous and more easy to manipulate.

Furthermore, it is also easy to regulate the point of explosion by controlling or adjusting the strength of the brake spring 10 *l* which will then exert a greater or lesser friction on the hub of the flywheel *s* thus giving rise, to a certain extent, to the rotation of this flywheel by the rotary movement of the mine.

15 The flywheel may obviously be located at any desired height in the mine. For instance, it may be located at the upper part thereof by suitably modifying the disposition of the locking levers of the percussion 20 pin.

This flywheel may also be provided externally of the mine or be merely constituted by weighted levers fulfilling the same function. Finally, it would also be possible to 25 use the explosive charge itself together with its receptacle *w* as a flywheel.

The invention is applicable to submarine mines of any kind.

What I claim is:

30 1. In a submarine mine in which the firing is controlled by the rotation of the mine in contact with a moving vessel, a flywheel provided in the interior of the mine, comprising displaceable stops for the locking members of the percussion pin.

2. In a submarine mine in which the firing is controlled by the rotation of the mine in contact with a moving vessel, a flywheel in the interior of the mine, the hub of which is mounted through the medium of a ball race on the body of the mine, a percussion pin, and locking members for the percussion pin controlled by the fly wheel.

3. In a submarine mine in which the firing is controlled by the rotation of the mine in contact with a moving vessel, a flywheel provided in the interior of the mine and comprising an inner flange formed with openings intended to form movable stops for the locking members of the percussion pin.

4. In a submarine mine in which the firing is controlled by the rotation of the mine in contact with a moving vessel, the combination of a percussion pin, locking members for the percussion pin, and a revolute member provided with means for holding and releasing the locking members, whereby the firing of the mine by the relative 55 movement between the mine and the revolute member is insured.

5. In a submarine mine in which the firing is controlled by the rotation of the mine in contact with a moving vessel, a percussion pin, a head or piston provided on the 65 percussion pin, swiveling levers supporting said head or piston, a flywheel mounted in the interior of the mine, a flange provided on the flywheel and comprising openings to form movable stops for said swiveling 70 levers.

6. In a submarine mine in which the firing is controlled by the rotation of the mine in contact with a moving vessel, rollers pivoted on the free ends of said levers, a flywheel mounted in the interior of the mine, a flange provided on the flywheel and comprising openings to form movable stops for 75 said swiveling levers.

7. In a submarine mine in which the firing is controlled by the rotation of the mine in contact with a moving vessel, a percussion pin, locking members for the pin, a flywheel carried by the mine and provided with movable stops for the locking members of 80 the mine, and means for holding the flywheel against movement.

8. In a submarine mine in which the firing is controlled by the rotation of the mine in contact with a moving vessel, a percussion pin, locking members for a pin, a revolute member provided with means for holding and releasing the locking members, and means for holding the revolute member against movement, said means being adapted 85 to be released when the mine is in the water.

9. In a mine, a revolute inertia member, means for holding the inertia member from movement, said means being adapted to be 100 released when the mine is in the water, a spring pressed percussion pin, releasable means for normally carrying said pin, and means engaging the percussion pin and controlled by the inertia member.

10. A float member and a revolute inertia member located within the same, means holding said members against relative displacement and adapted to be released when the float is in the water, a spring-pressed 110 firing pin, jaws normally carrying said pin, and means released by displacement of said members for disengaging said jaws to release said firing pin.

In testimony whereof I have hereunto set 115 my hand at Rome, this second day of September, 1914.

GIOVANNI EMANUELE ELIA.
